UNITED STATES PATENT OFFICE.

CHARLES FORTH, OF OTTAWA, ONTARIO, CANADA, ASSIGNOR TO FLEXIBLE METAL HOSE COMPANY LIMITED, OF OTTAWA, ONTARIO, CANADA.

SWITCH-LOCK.

1,267,998.

Specification of Letters Patent. Patented May 28, 1918.

Application filed September 30, 1916. Serial No. 123,084.

To all whom it may concern:

Be it known that I, CHARLES FORTH, a citizen of the United States of America, residing at 26 Wellington street, in the city 5 of Ottawa, Province of Ontario, Dominion of Canada, have invented certain new and useful Improvements in Switch-Locks, of which the following is a specification.

This invention relates to improvements 10 in switches and particularly refers to the lock thereof and the objects of the invention are to prevent the key being withdrawn from the lock when the switch is open, to permit of the automatic locking 15 of the switch, to facilitate in assembling the lock to the switch lever, to render the lever capable of being used on any switch at present in use, to simplify the construction and generally to adapt the several 20 parts to better perform the functions required of them.

With the above and other objects in view the invention consists essentially of the improved construction particularly described 25 and set forth in the following specification and accompanying drawings forming part of the same.

In the drawings,

Figure 1 is a side elevation of a switch 30 embodying the present invention.

Fig. 2 is a longitudinal section of the switch lever showing the location of the lock therein.

Fig. 3 is an enlarged transverse section 35 through the line 2—2 of Fig. 2.

Fig. 4 is an enlarged perspective view of the lock.

Fig. 5 is a plan view of the lock.

Fig. 6 is a fragmentary perspective view 40 of a part of the lock showing the tongue engaged by the locking bolt and tumbler lever.

Like characters of reference refer to like parts in the several drawings.

Referring to the drawings, A represents a 45 switch stand of any usual construction provided with the lever B, and carrying the tongue C having an orifice therethrough designed to coact with the lock D operatively mounted on the said lever.

The lever B is formed with a bifurcated 50 end, the arms 11 of which are pivotally attached to the switch stand A, and is further provided with an integral casing E em-

braced by the said arms intermediate of their length and designed to contain the 55 parts of the lock.

The side members of the casing E are formed by the arms 11, while the ends 12 and the top 13 are integral therewith, the said top carrying a curvilinear hollow projection 14 adapted to house the end of the tongue C, and being further provided with a keyhole therethrough above which the cover 15 is pivotally mounted, so preventing moisture and dirt from accumulating in the 60 interior of the lock. The casing is completed by the removable bottom 16 carrying the lock mechanism operatively mounted thereon.

The bottom 16 is formed with a bifurcated 70 end, the arms 17 of which are provided with end flanges 18, the said bottom being further provided with lateral flanges 19 having orifices 20 therethrough adapted to register with orifice 21 in the side walls of the casing 75 E, to which the bottom is secured by pins or the like.

Pivotaly mounted on the upper face of the bottom 16 is a locking bolt 22 having an offset beveled end 23, and provided intermediate of its length with a lateral projection 24, the inner edge of the locking bolt being provided with a curvilinear projection 25 embracing the key spindle 26 and cut away to form a shoulder 27.

The end of the locking bolt 22 remote from the end 23 is provided with a tongue 28 adapted to abut with the outer face of a U-shaped member 29 formed integral with the bottom 16, which member is designed to 90 embrace one end of the spiral spring 30 the other end of the spring engaging the projection 24.

Co-acting with the locking bolt 22 is a tumbler lever 31 pivotally mounted intermediate of its length to the upper face of the bottom 16, and provided with an offset end 32, the under face of which is substantially beveled, the said lever being provided intermediate of its length with a projection 33 100 designed to coact with the shoulder 27 of the locking bolt.

This tumbler is spring controlled and is provided at the end remote from the offset end 32 with an offset tongue 34 having an 105 orifice therethrough, with which one end of

the spring 35 mounted on the pin 36 engages, the other end of the spring being anchored to the bottom 16.

The assembly of the lock and lever will 5 be readily understood from the foregoing description.

When the switch is being opened, the wards of the key engage the locking bolt 22 and laterally displace it against the action of the spring 30 and disengage the end 10 23 from the orifice in the tongue C, whereupon the lever is rotated upwardly and the switch turned into the desired position.

The locking bolt 22 on being thus displaced permits the tumbler lever 31 to be rotated under the action of the spring 35, and the projection 33 engages with the shoulder 27 so retaining the locking bolt in a retracted position, and it will be evident that since the curvilinear projection 25 20 underlies the keyhole in the top of the casting E it is quite impossible to withdraw the said key while the switch is open.

In closing the lever the tongue C engages 25 with the offset beveled ends 23 and 32 of the locking bolt 22 and tumbler lever 31 respectively, displacing the same laterally and when the lever B has been brought to its closed position the end 23 of the locking 30 bolt 22 engages with the orifice in the tongue C while the end 32 of the tumbler lever engages with the lateral face of the said tongue as illustrated in Fig. 6.

It will be readily seen that the bevel on 35 the end 23 of the locking bolt 22 is shorter than the bevel on the end 32 of the tumbler lever 31, so that the locking bolt is displaced while the tongue C is still wiping the end 32, which is subsequently displaced so 40 allowing the key to be withdrawn, and causing the projection 33 to coat with the shoulder 27 and prevent the locking bolt 22 becoming inadvertently displaced.

As many changes could be made in the 45 above construction and many apparently widely different embodiments of my invention, within the scope of the claims, constructed without departing from the spirit or scope thereof, it is intended that all matter contained in the accompanying specification and drawings shall be interpreted as illustrative and not in a limiting sense.

What I claim as my invention is:

1. The combination with a switch stand, 55 including a switch lever and tongue, of a lock comprising a removable plate having a bifurcated end, a locking bolt pivotally mounted on the plate, and provided with an offset beveled end operating transversely across the bifurcated end of the plate, and

laterally displaceable means coacting with and designed to hold the locking bolt in an open position.

2. The combination with a switch stand, including a switch lever and tongue, of a lock comprising a removable plate having a bifurcated end, a locking bolt pivotally mounted on the plate, provided with an offset beveled end operating transversely across the bifurcated end of the plate, a curvilinear 70 projection on the locking bolt provided with a suitable shoulder, and a pivotally mounted tumbler lever coacting with the shoulder and provided with an offset beveled end operating transversely across the bifurcated 75 end of the plate.

3. The combination with a switch stand, including a switch lever and tongue, of a casing integral with the switch lever and provided with a hollow curvilinear projection, a removable plate coacting with the lever, a spring controlled locking bolt pivotally mounted on the plate provided with an offset beveled end, and a spring controlled tumbler lever coacting with the locking bolt and provided with an offset beveled end.

4. The combination with a switch stand including a switch lever and tongue, of a lock comprising a pivotally mounted locking bolt provided with an offset beveled end, a curvilinear projection on the inner edge of the locking bolt provided with a shoulder, a spring controlled tumbler lever provided with an offset projection intermediate of its length coacting with the shoulder, and having an offset beveled end, as and for the purpose specified.

5. In combination with a switch stand, including a switch lever and tongue, of a locking bolt pivotally mounted on the plate, provided on one end with an offset beveled part operating transversely across the bifurcated end of the plate, the opposite end of the locking bolt having a projection adapted to abut with the outer face of a U shaped member, a spring having one end bearing on the inside of the U shaped member and its other end bearing on a projection on the locking bolt provided with a suitable shoulder and a pivotally mounted tumbler lever co-acting with the shoulder and provided with an offset beveled end operating transversely across the bifurcated end of the plate.

In witness whereof I have hereunto set my hand in the presence of a witness.

CHARLES FORTH.

Witness:

RUSSEL B. SMART.
